(57) **CLAIM**

The ornamental design for combined luggage and carrier, as shown and described.

DESCRIPTION

FIG. 1 is a left front perspective view of combined luggage and carrier according to my new design;

FIG. 2 is a left side view of combined luggage and carrier;

FIG. 3 is a top view of combined luggage and carrier;

FIG. 4 is a bottom view of combined luggage and carrier;

FIG. 5 is a back view of combined luggage and carrier; and,

FIG. 7 is a left side perspective view of the combined luggage and carrier in a state of use.

The broken lines illustrate environment and form no part of the claimed design.

The right side views are mirror images of the left side views.
